DESIGN FOR A WALLET

Robert S. Berens, New York, N. Y.

Application October 19, 1944, Serial No. 115,877

Term of patent 14 years

(Cl. D87—3)

To all whom it may concern:

Be it known that I, Robert S. Berens, a citizen of the United States of America and a resident of the county of Kings, Borough of Brooklyn, city and State of New York, have invented a new, original, and ornamental Design for a Wallet, of which the following is a specification, reference being had to the accompanying drawings forming a part thereof.

On the drawings:

The back of the wallet (not shown) is substantially plain.

I claim:

The ornamental design for a wallet, as shown and described.

ROBERT S. BERENS.
